US00D980810S

(12) **United States Design Patent** (10) **Patent No.:** **US D980,810 S**
Kondo et al. (45) **Date of Patent:** **** Mar. 14, 2023**

(54) **INTEGRATED CIRCUIT CARD**

- (71) Applicant: **KIOXIA Corporation**, Tokyo (JP)
(72) Inventors: **Atsushi Kondo**, Yokohama (JP);
Katsuyoshi Watanabe, Fujisawa (JP)
(73) Assignee: **KIOXIA Corporation**, Tokyo (JP)
(**) Term: **15 Years**
(21) Appl. No.: **29/747,965**
(22) Filed: **Aug. 26, 2020**

(30) **Foreign Application Priority Data**

- Feb. 27, 2020 (JP) ..... JP2020-003737 D

Primary Examiner — Christy Nemeth*Assistant Examiner* — Leah E Hoeferkamp(74) *Attorney, Agent, or Firm* — Banner & Witcoff, Ltd.(57) **CLAIM**

The ornamental design for an integrated circuit card, as shown and described.

DESCRIPTION

FIG. 1 is a front perspective view of an integrated circuit card showing our new design,

FIG. 2 is a rear perspective view thereof,

FIG. 3 is a front elevational view thereof,

FIG. 4 is a rear elevational view thereof,

FIG. 5 is a top plan view thereof,

FIG. 6 is a bottom plan view thereof,

FIG. 7 is a left side elevational view thereof; and,

FIG. 8 is a right side elevational view thereof.
